ABSTRACT OF THE DISCLOSURE

A method and apparatus for receiving cartons in a flat, collapsed or folded condition; setting these cartons up in an open condition; folding some of the flaps of the carton; loading containers into the carton; inserting partitions between the containers in the carton; and, subsequently folding the unfolded bottom flaps of the carton for sealing.

The apparatus includes a carton magazine which receives the flat, collapsed cartons in an ordered arrangement. A stripping means moves cartons from the ordered arrangement one at a time substantially parallel to the side panels thereof and into engagement with opposed, relatively movable suction means. The suction means are moved away from each other to set up the carton in an open condition. A pusher means of a conveyor means then engages and moves the opened carton longitudinally of the machine to a loading position while closing two of the bottom flaps thereof.

An infeed conveyor receives containers in an ordered arrangement and disposes them over the opened carton when it is in the loading position. A loading suction means engages the containers to be loaded into the carton and moves them down into the carton as opening means engage the top flaps of the carton and hold them open while the carton is being loaded. A primary conveyor of the conveyor means then moves the loaded carton longitudinally of the apparatus and into partition inserting position.

A partition inserting means then places partitions in the carton between the containers therein to protect the containers during shipment. The primary conveyor and a secondary conveyor of the conveyor means then move the loaded carton to a flap folding means. A bar conveyor of the conveyor means moves the carton through the flap folding means to fold the unfolded bottom flaps of the carton for final sealing of the carton.

BACKGROUND OF THE INVENTION

(1) Field of the invention

This invention relates generally to a method and apparatus for packing collapsible cartons and more particularly to a method and apparatus for removing flat, collapsed or folded cartons from an ordered arrangement; setting the cartons up in an open condition; loading the cartons with containers arranged in a predetermined pattern; then placing partitions individually between the containers in the carton and subsequently folding the flaps of the carton for sealing.

(2) Discussion of the prior art

Many packaging machines which set up collapsed cartons, fill these cartons with containers, and fold the flaps thereof have been available on the market. All of these prior art machines have, however, either placed containers in the carton with no partitions between the containers or placed containers in a carton which already had the partitions therein. When relatively fragile containers were placed in the previously partitioned cartons, the alignment of the containers with the partitions became critical

2

and therefore required extensive maintenance to prevent breakage and jamming. Moreover, these prior art machines which opened the collapsed cartons have usually been complicated in construction so as to require extensive adjustment and repairs.

When partitions had to be utilized with prior art packaging machines, these partitions were usually assembled out of the carton and then inserted into the carton by hand prior to placing the containers therein. This procedure was not only time consuming and therefore costly, but also increased the likelihood of damage to the partition during assembly.

SUMMARY OF THE INVENTION

These and other problems and disadvantages associated with the prior art are overcome by the invention disclosed herein by loading the containers in the opened carton without the partitions therein and subsequently inserting the partitions between the containers in the carton. This substantially reduces the complexity of the structure necessary to successfully load the containers in the carton and results in lower manufacturing and maintenance costs.

By individually inserting the partitions into the carton between the containers, very little pressure is exerted on the containers during this operation. This reduces the likelihood of the containers being punctured. Moreover, since the partitions are inherently assembled as they are inserted in the cartons between the containers, the separate assembly steps normally associated with the prior art are eliminated. This further reduces the cost of packaging and the damage to the partitions as a result of excessive handling.

Moreover, the invention provides a simple magazine and stripping means which moves a collapsed carton from an ordered arrangement into engagement with opposed suction means so that the carton can be quickly and easily opened with a minimum of equipment. This also results in reducing the cost of production and maintenance for the invention.

The means which conveys the cartons between the different sections of the machine operates continuously, and the cartons are independently stopped at each section. This alleviates any synchronization problems that are normally associated with an intermittent type conveyor system. Therefore, by simplifying the components necessary in the invention, a high rate of production can be maintained while the operating cost thereof can be kept to a minimum.

Therefore, it is one of the objects of the invention to provide an apparatus for filling cartons with containers that is durable and efficient in operation.

Another object of the invention is to provide a method of an apparatus for filling cartons with containers so that the containers are not punctured or otherwise damaged.

Another object of the invention is to provide a method of and apparatus for filling cartons with containers in which the cartons are moved along a substantially straight horizontal path.

Another object of the invention is to provide a method of and apparatus for filling cartons with containers in which the containers are automatically placed in the carton in a prescribed pattern.

Another object of the invention is to provide a method of and apparatus for filling cartons with containers in which the containers are handled only minimally.

Another object of the invention is to provide a method of and apparatus for filling cartons with containers in which the cartons are set up from a flat, collapsed condition.

Another object of the invention is to provide a method of and apparatus for filling cartons with containers in which part of the flaps of the container are automatically closed.

Another object of the invention is to provide a method and apparatus for filling cartons with containers in which partitions are positioned between the containers after the containers have been placed in the cartons.

Another object of the invention is to provide a method of and apparatus for filling cartons with containers in which the partitions are assembled as they are placed between the containers.

Another object of the invention is to provide an apparatus for filling cartons with containers that is simple in construction and substantially foolproof in operation.

The apparatus of the invention includes a carton opener section which receives cartons in a flat, collapsed condition and sets them up individually in an open position; a carton packing section which receives containers and loads the containers into the opened cartons; a partition inserter section which inserts partitions between the containers in the loaded cartons; a flap folder section which folds the flaps of the carton for sealing; and, a conveyor section which moves the cartons through the aforementioned sections.

The carton opener section includes a carton magazine which receives the cartons in a flat, collapsed condition, a stripper means associated with the magazine for removing the flat, collapsed cartons from the ordered arrangement one at a time and along a path substantially parallel to the side panels of the cartons; opposed first and second suction means associated with the stripper means and into engagement with which the stripper means moves the flat, collapsed cartons from the magazine. The suction means engage opposite side panels of the flat collapsed carton and the first suction means moves away from the second suction means to open the carton. The second suction means releases the side panel of the carton after the first suction means has moved a predetermined distance and the first suction means continues to open the carton around a deflection member until the carton is fully opened.

The conveyor section moves the opened cartons along a longitudinal path through the apparatus and includes a carton pusher which moves the opened carton from the carton opener section to the carton packing section, a primary belt conveyor which moves the carton through the carton packing section and partition inserting section; a secondary belt conveyor which moves the carton from the primary belt conveyor to the flap folding section; and a bar conveyor which moves the carton from the secondary belt conveyor through the flap folding section. In addition to moving the opened carton from the carton opener section to the carton loading section, the carton pusher folds the two bottom flaps of the carton positioned transversely of the longitudinal path.

The carton packer section includes an infeed container conveyor means which receives containers to be packed in an ordered arrangement and positions a selected number of these containers in the carton packer section, and a loading suction means which engages the containers position in the packer section and loads them into the opened carton carried by a carton lift in the conveyor section. A funnel means engages the top flaps of the opened carton and holds them open as the loading suction means loads the containers into the carton. After the loading suction means has loaded the carton, the carton lift lowers the loaded carton onto the primary belt conveyor which transfers the loaded carton to the partition inserter section of the machine.

The partition inserter section includes a first inserter means and a second inserter means spaced longitudinally downstream of the first inserter means in the machine. That portion of the conveyor section under the partition inserter section includes a first stop means operatively associated with the first inserter means and a second stop means associated with the second inserter means.

The first stop means engages the loaded carton as it enters the partition inserter section and holds it in position under the first inserter means. The first inserter means

includes a magazine which receives a plurality of first partitions in an ordered arrangement and an inserter assembly which moves the first partitions individually into successive loaded cartons as they are held in position by the first stop means.

The second stop means receives the carton as it passes the first stop means and holds it in position under the second inserter means. The second partition inserter means places a second partition in each loaded carton transversely of the first partition as it is held by the second stop means. The primary belt conveyor is effective to transfer the loaded carton between the first and second stop means and onto the secondary belt conveyor when the second stop means releases the loaded carton.

The secondary belt conveyor moves the loaded and partitioned carton into engagement with the bar conveyor. The bar conveyor then moves the carton through the flap folding section. This folds the remaining unfolded bottom flaps of the loaded and partitioned carton and the carton passes out of the machine for processing by other equipment.

These and other objects, features and advantages of the invention will become more apparent upon consideration of the following specification and accompanying drawings in which like characters of reference designate corresponding parts throughout and wherein:

BRIEF DESCRIPTION OF THE DRAWINGS

FIG. 1 is a perspective view of one embodiment of the invention;

FIG. 2 is a schematic perspective view showing the stages of the carton being filled;

FIG. 3 is a flow diagram showing the steps of the method of the invention;

FIG. 4 is a partial side elevational view of the carton opener and conveyor sections of the invention of FIG. 1 with the front side panel removed and portions thereof broken away to show the interior construction thereof;

FIG. 5 is an end view of the left end of the machine of FIG. 1;

FIG. 6 is a cross-sectional view taken along line 6—6 in FIG. 4;

FIG. 7 is a cross-sectional view taken along line D—D in FIG. 6;

FIG. 8 is a cross-sectional view taken on line 8—8 of FIG. 4;

FIG. 9 is a partial front elevational view of the carton stripping means of the carton opening section;

FIG. 10 is a partial elevational view of the carton packer and conveyor sections of the invention of FIG. 1 with the front side panel removed and portions thereof broken away to show the interior construction thereof;

FIG. 11 is a cross-sectional view taken along line 11—11 in FIG. 10;

FIG. 12 is an enlarged cross-sectional view taken along line 12—12 in FIG. 10 and showing the drop table unit of the carton packer section;

FIG. 13 is a partial top plan view of the drop table unit taken along line 13—13 in FIG. 12 and showing the drop gates;

FIG. 14 is a bottom plan view of the drop table unit showing the funnel gates thereof and taken along line 14—14 in FIG. 15;

FIG. 15 is an elevation of the drop table unit taken along line 15—15 in FIG. 14;

FIG. 16 is a partial elevational view of the partition inserter and conveyor sections of the invention of FIG. 1 with the front side panel removed and portions thereof broken away to show the interior construction thereof;

FIG. 17 is a partial cross-sectional view of the conveyor section taken along line 17—17 in FIG. 16;

FIG. 18 is a partial elevational view of the carton packer section with portions thereof broken away to show the interior construction thereof;

FIG. 19 is a partial cross-sectional view taken along line 19—19 in FIG. 18;

FIG. 20 is a cross-section along line 20—20 of FIG. 21;

FIG. 21 is a partial right end elevational view of the invention of FIG. 1 showing the flap closing section;

FIG. 22 is a cross-sectional view taken along line 22—22 in FIG. 20;

FIG. 23 is a partial pneumatic schematic diagram of the control circuit for the carton opener and conveyor sections of the invention;

FIG. 24 is a partial pneumatic schematic diagram of the control circuit for the carton packer and conveyor sections of the invention; and,

FIG. 25 is a partial pneumatic schematic diagram of the control circuit for the partition inserter and conveyor sections of the invention.

These figures and the following detailed description disclose specific embodiments of the invention, however, the inventive concept is not limited thereto since it may be embodied in other forms.

DESCRIPTION OF ILLUSTRATIVE EMBODIMENTS

Reference to FIGS. 1, 4, 10, 16 and 20 of the drawings will show that the apparatus of the invention has been divided into sections for purposes of description. The sections are carried by a frame 10 with each section performing an operation on the carton into which containers are placed. The sections are: (1) a carton opener section which receives the flat, collapsed cartons and opens them for loading; (2) a carton packer section which receives the opened carton from the carton opener section and places the containers in the carton; (3) a partition inserter section which receives the loaded cartons from the carton packer section and individually inserts partitions between the containers in the cartons; (4) a flap closing section which receives the loaded and partitioned cartons from the partition inserter section and closes the flaps of the carton for sealing; and (5) a conveyor section for transferring the cartons between the above sections along a prescribed path.

The cartons C, shown in FIG. 2, utilized by the invention are of conventional corrugated board construction which will fold into a flat, collapsed condition for shipment and which can be opened for the receipt of articles therein by forcing the side panels P thereof apart and subsequently folding the flaps F over to complete the carton. The containers A placed in the cartons C are illustrated as conventional fiberboard containers having an angled top construction B; however, other types of containers may be utilized with the invention. The invention is especially adapted to package containers which are fragile, as are the containers A shown, without damage thereto.

The frame 10 of the invention comprises a pair of vertical standards 11, 11' and 12, 12', the standards 11 and 11' being positioned on opposite sides of the left end of the machine as seen in FIG. 1 of the drawings and the standards 12, 12' being positioned on opposite sides of the right end of the machine. The standards 11 and 12 mount a front side panel 14 therebetween and the standards 11' and 12' mount a rear side panel 15 therebetween. Cross-braces 17, as seen in FIGS. 4 and 20, join the standards 11, 11' and 12, 12' to form a rectangular frame. It will also be seen that the standards 11, 11' are taller than the standards 12, 12' and extend above the side panels 14 and 15 to support one end of an infeed conveyor, as will be explained hereinafter.

A pair of first intermediate upright supports 16, 16', a pair of second intermediate upright supports 18, 18', and a pair of third intermediate upright supports 19, 19' are positioned on the side panels 14 and 15 between the standards 11 and 12, the supports 16, 18 and 19 being affixed to the panel 14 and the supports 16', 18' and 19' being affixed to the panel 15 opposite the supports 16, 18 and 19. The supports 16, 16', 18, 18' and 19, 19' are taller than the standards 11, 11' and extend upwardly past the standards 11 to carry additional assemblies as will be explained hereinafter. The standards 11, 11', 12 and 12' and the

supports 16, 16', 18, 18', 19 and 19' rest on the floor to support the frame 10.

The rear side panel 15 has an offset portion 13 at the left end thereof to accommodate the components of the 5 carton opener sections. This offset portion 13 is supported by the substandards 23 as best seen in FIG. 6.

CARTON OPENER SECTION

The carton opener section of the invention, as seen in 10 FIGS. 4-7, and comprises a carton magazine 20 which carries cartons C in a flat, collapsed condition; a carton stripper 21 which strips the cartons C from the magazine 20 and positions them for opening; and a carton opening assembly 22 which receives the cartons C from the strip 15 per 21 and opens the cartons C for loading with containers A.

The carton opener section is carried by a substructure S which includes a mounting plate 25 extending between the upper edges of the side panel 14 and the offset portion 20 13 of the side panel 15 at the left end of the frame 10 as seen in FIGS. 4, 5 and 6. A transversely disposed vertically extending carriage beam 26 is attached to the upper surface of the mounting plate 25 at the rear portion thereof. A like carriage beam 28 is attached opposite the beam 26 on that segment of the offset portion 13 of the side panel 15 connected to the elongated portion of the panel 15. An undercarriage brace 29 extends between the lower portions of the beams 26 and 28 at the rear thereof and carries the magazine 20 thereon.

30 Magazine.—The magazine 20 includes an undercarriage 30 carried at its forward end by the brace 29 and at its rearward end by a pair of braces 31 attached to the offset portion 13 of the side panel 15. The flat, collapsed cartons C rest on the top of the undercarriage 30 and side 35 rails 32 maintain them in position as seen in FIG. 5. By adjusting the braces 31, the angle α of the undercarriage 30 with respect to the horizontal can be varied; however, the angle α shown is approximately fifteen (15) degrees with the forward end of the undercarriage 30 being lower than the rearmost end thereof.

40 A pressure weight holder 34 is movably carried along the top of the undercarriage 30 and is urged forwardly along the undercarriage by the force of gravity acting on a weight W carried in the holder 34. A component of the 45 force of gravity acts along the undercarriage 30 to force the cartons C forwardly along the undercarriage 30. This component of force is selectively variable by changing the size of the weight W or the angle of the undercarriage 30 with respect to the horizontal. A refracting mechanism 50 5 is provided to move the holder 34 rearwardly along the undercarriage 30 to refill the magazine 20 with cartons.

The forward motion of the cartons C along the undercarriage 30 is arrested by a check substructure 36 mounted between the carriage beams 26 and 28 as seen 55 in FIGS. 4 and 6. The check substructure 36 includes right and left check sills 49 and 50 respectively, the right check sill 49 being adjustably attached to the right carriage beam 28 through a support element 51 and the left check sill 50 being adjustably attached to the left carriage

60 beam 25 through a support element 52. The check sills 49 and 50 are positioned so that they engage the flat, collapsed cartons C along the vertical edges thereof as the weight holder 34 forces the cartons C forwardly in the machine. It will be seen that the sills 49 and 50 and the weight holder 34 maintain the collapsed cartons C vertical. The sills 49 and 50 are hinged as at 47, and that portion of the sills 49 and 50 engaging the edges of the cartons C are spring urged rearwardly in the machine just sufficiently to retain the cartons, yet release each carton 70 as the carton opening assembly starts to open it as explained hereinafter.

The check substructure 36 also includes a pair of vertical, spaced apart slide guides 54 which are positioned between the beams 26 and 28 by a pair of horizontal spacers 75 55 carried by and between the carriage beams 26 and 28.

The rearwardly facing slide surfaces 56 thereof are in alignment with the sills 49 and 50 so that the flat, collapsed cartons C will rest against the surfaces 56 and the sills 49 and 50 to check their forward movement. The forwardmost carton C in the magazine 20 is positioned forwardly of the forwardmost end of the undercarriage 30 when motion is arrested by the check means 36. This allows the forwardmost carton C to be displaced downwardly in front of the undercarriage 30 by the stripper 21 for opening. The sills 49 and 50 are sufficiently long to still retain the edges of the stripped carton C, yet the slide guides 54 are sufficiently short for the top of the displaced carton C to clear the bottoms thereof during the opening of the carton C.

Carton stripper.—The carton stripper 21 displaces the forwardmost carton C in the magazine 20 downwardly into carton opening position and includes a vertically movable stripper plate 58 having a thickness substantially equal to or slightly less than the total thickness of a flat, collapsed carton C and a width sufficient to engage a major portion of the uppermost edge of the collapsed cartons C. The stripper plate 58 slidably passes along the surfaces 56 on the rearward side of the slide guides 54 and displaces the forwardmost carton C downwardly out of the magazine 20 and into carton opening position.

The stripper plate 58 is slidably positioned along the surfaces 56 by a piston rod 59 attached to the plate 58. The piston rod 59 is selectively positioned by a fluid cylinder 60 of conventional design. The cylinder 60 is maintained in a vertical position through a support channel 61 centrally carried between the carriage beams 26 and 28 by a pair of horizontal crossbraces 62 attached to the beams 26 and 28.

The support channel 61 also includes a vertically disposed guide recess along the rearmost side thereof. A vertical follower 65 is slidably retained in the recess and is attached to the stripping plate 58. The follower 65 has a thickness substantially equal to the stripping plate 58 so that as the stripping plate 58 engages the top of the forwardmost flat, collapsed carton C and moves the carton downwardly into carton opening position, the follower 65 prevents the cartons C behind the forwardmost carton from moving forwardly into interference with the stripping plate 58 as it is returned to its upper position by the cylinder 60.

Since the flat, collapsed cartons C in the magazine 20 are maintained vertically and since the undercarriage 30 is maintained at the angle α with respect to the horizontal, there is sometimes a tendency for the cartons C in the magazine 20 to tip forwardly at the top without the bottom thereof being moved. To overcome this problem, an alignment mechanism 38 is provided under the forward portion of the undercarriage 30 as seen in FIGS. 6 and 7. The mechanism 38 shifts the bottom of the cartons C forwardly as the top thereof tends to tip.

The alignment mechanism 38 includes a wedge shaped shifting block 39 mounted on the end of a piston rod 40. The piston rod 40 is slidably carried in a conventional fluid container 41 mounted under the undercarriage 30. The cylinder 41 is positioned so that the upper surface of the block 39 engages the bottom of the forward cartons C when the piston rod 40 is extended but is displaced below the cartons C when the piston rod 40 is retracted. This is effective to shift the bottoms of the cartons C into vertical alignment as the piston rod 40 is extended while the stripping plate 58 is in its upper position.

Carton opening assembly.—The carton opening assembly 22 receives the forwardmost flat, collapsed carton C as the stripping plate 58 moves the carton C downwardly for opening. Included in the opening assembly 22 is a split, horizontal slide table 66 carried between the side panel 14 and the offset portion 13 of the side panel 15. The table 66 has a rear section 66a and a front section 66b. The table 66 provides vertical support for the carton C as it is being opened, and is split to allow the

conveying means to move therethrough and transfer the opened carton C to the carton packer section. The bottom of the flat, collapsed carton C rests on the rear section 66a after the carton is stripped, and when the carton has been set up in an opened condition one side thereof rests on the front section 66b while the opposite side thereof still rests on the rear section 66a.

Also included in the opening assembly 22 is a stabilizer 68 positioned under the magazine 20 and just rearwardly of the position of the flat, collapsed carton C that has been stripped into opening position and shown in FIGS. 6 and 7. The stabilizer 68 momentarily retains the rear side panel P of the stripped carton C to initiate the opening operation and includes a mounting bracket 69 carried by the frame 10 which mounts guide plate 70. The guide plate 70 carries a fluid cylinder 71 having a piston rod 72 extending forwardly through the guide plate 70 to receive on the extending end thereof a suction cup carriage 74. The suction cup carriage 74 mounts a pair of horizontally spaced, forwardly facing suction cups 75 thereon. Suction tubes 65 connected to the suction cups 75 extend rearwardly therefrom through appropriate apertures in the plate 70 to serve as guides for the stabilizer 68. The suction tubes 76 are connected through a vacuum line VL to a conventional vacuum source VS as will be explained hereinafter.

The suction cups 75 can be selectively extended by the piston rod 72 into engagement with side panel P of the carton C that has been stripped from the magazine 20 and a vacuum is exerted through the cups 75 to hold the panel P. From FIG. 7 of the drawings, it will be noted that the stabilizer 68 is positioned at the left portion of the stripped carton C as viewed from the front of the machine so that the suction cups 75 will engage the appropriate rear side panel P to retain it during the initial opening of the flat, collapsed carton C. As soon as the carton C is initially opened, the vacuum is dropped to release the panel P and the piston rod 72 retracted to move the cups 75 away from the carton C to restart the next opening operation.

The component of the opening assembly 22 that primarily performs the opening of the carton C is an opener arm unit 78 which moves rearwardly into the machine to engage the stripped, flat, collapsed carton C through a suction connection and then moves forwardly in the machine to fully open the carton. The opener arm unit 78 includes a generally horizontally oriented arm 79 having a pivot yoke 80 at the left end thereof and a driving yoke 81 at the right end thereof as seen in FIG. 4. A trunnion sleeve 82 is provided around the arm 79 intermediate its ends which has diametrically opposed, vertically oriented hollow trunnions 84. The opener arm 78 is carried by a vertical gudgeon pin 85 extending through appropriate apertures in the pivot yoke 80 and by a vertical trunnion pin 86 extending through the hollow trunnions 84.

The gudgeon pin 85 is carried by the bifurcated end of pivot link 88 and the other end of link 88 is pivotally carried on a vertically extending arbor 89. The arbor 89 is mounted on the left side of the mounting plate 25. The trunnion pin 86 is carried by one end of a drive link 90 which has its other end pivotally carried by a vertical spindle 91. The spindle 91 is mounted on the right side of the mounting plate 25. The arm 79, the pivot link 88, the drive link 90, and the mounting plate 25 define a four bar linkage.

As seen in FIG. 6, the linkage is driven by a fluid cylinder 92 having one end pinned to the mounting plate 25 and a piston rod 94 extending forwardly from the other end thereof. The extending end of the piston rod 94 is pinned to the trunnion pin 86 between the drive link 90 and the lower trunnion 84. The arm 79 is pivoted rearwardly as the piston rod 94 is retracted and pivoted forwardly 16 when it is extended.

A suction manifold 95 mounting a plurality of rearwardly facing suction cups 98 thereon is pivotally connect-

ed to the arms of the driving yoke 81 by a vertical yoke pin 96 extending through appropriate apertures in the yoke 81 and the manifold 95. When the arm 79 is pivoted rearwardly in the machine, the cups 98 are moved into engagement with the appropriate front side panel P of the flat, collapsed carton C that has been stripped from the magazine 20. The suction cups 98 then engage the carton C under a vacuum drawn through the vacuum line VL connected thereto. As the arm 79 is pivoted forwardly, the suction cups 98 move the front side panel P forwardly in the machine to open the carton C.

In order to maintain the suction cups 98 parallel with the longitudinal centerline of the machine, a positioning linkage is provided on the arm 79. Although different types of linkages may be utilized, the particular linkage illustrated utilizes an alignment chain 100' carried by sprockets 101' fixedly mounted on the upper ends of the gudgeon pin 85 and the yoke pin 96. To make this arrangement operative, the gudgeon pin 85 is fixed with respect to the bifurcated pivot link 88 and rotatable with respect to the pivot yoke 80. The yoke pin 96 is fixed with respect to the manifold 95, and rotatable with respect to the driving yoke 81. Therefore, as the arm 79 is pivoted, the suction cups 98 will be maintained parallel to the centerline of the machine.

The forwardly facing suction cups 75 of the stabilizer 68 retain the rear side panel P of a stripped carton C until the panels P are separated by the cups 98 to start the opening operation. The rear side panel P is then released and the carton C fully opened by the cups 98. To insure opening of the carton C, a vertically positioned deflector 102' is mounted on the left carriage beam 26 between the carton stripper 21 and the opener arm unit 78. The deflector 102 has an arm receiving cutout 103' in the forward portion thereof to prevent interference between the deflector 102 and the arm 79 when the arm 79 is fully pivoted rearwardly to engage a stripped carton C. A deflection surface 104' is provided by the deflector 102 which engages one of the end panels of the carton C as it is moved forwardly by the opener arm 78 and deflects the carton C into an opened position in alignment with the longitudinal centerline of the machine. A pair of positioning bars 107 engage the front panel of the carton C when it is fully open to maintain the carton in position.

CONVEYOR SECTION

The conveyor section moves the open carton C along a prescribed path X parallel to the longitudinal centerline of the machine and through the various sections of the machine as the carton C is loaded with containers, has the partitions inserted between the containers, and the bottom flaps thereof closed for subsequent sealing. The conveyor section includes a carton pusher 100 which moves the opened carton C along the path X from the carton opener section to the carton loading section; a primary conveyor unit 101 which receives the opened carton C in the carton packer section and transfers the carton C along the path X from the carton packer section through the partition inserting section and into the flap closing section; a secondary belt conveyor 102 which transfers the loaded carton C along the path X from the primary belt conveyor 101 into the flap folding section; and, a bar conveyor 104 which receives the loaded carton C from the conveyor 102 and moves the loaded carton C through the flap folding section.

Carton pusher.—The carton pusher 100 includes a pair of upstanding pusher brackets 105 and 105' which pass between the front section 66b and rear section 66a of the slide table 66 to engage the opened carton C. Each pusher bracket 105 and 105' has a pushing recess 106 in the upper portion thereof to engage the opened carton C and move the carton to the right along the path X as seen in FIG. 4. Each pusher bracket 105 and 105' also includes a wedge shaped projection 108 which is positioned below the pushing recess 106 and is effective to engage the left bottom

flap F of the opened carton C as the pusher brackets 105 are moved to the right as seen in FIG. 4. The wedge shaped projections 108 fold the left bottom flap F as seen in FIG. 4 of the opened carton C up into a horizontal plane as the pusher brackets 105 and 105' are moved to the right. This serves to close the left bottom flap of the opened carton C while simultaneously advancing the carton C to the right along the path X to the carton loading section in the machine.

10 The pusher brackets 105 and 105' are mounted on a carriage 109. The carriage 109 is slidably mounted on a pair of generally horizontal, longitudinally extending guide rods 110. The guide rods 110 are mounted at the left ends by a member 111 affixed between the side panels 14 and 15. The right ends of the rods 110, as seen in FIG. 4, are mounted in a guide assembly 112. This mounts the rods 110 parallel to each other so that the carriage 109 may be slidably moved therealong.

For selectively positioning the carriage 109 and thus the 20 pusher brackets 105 and 105' along the guide rods 110, a fluid cylinder 114 is pivotally mounted in the guide assembly 112 and has its piston rod 115 pinned to the carriage 109. Therefore, it will be seen from FIG. 4 that as the piston rod 115 is extended from the fluid cylinder 25 114, the pusher brackets 105 and 105' will be moved to the left along the guide rods 110 and as the piston rod 115 is retracted, the pusher brackets 105 and 105' will be moved to the right.

Since the pusher brackets 105 and 105' are moved sufficiently far to the left as shown in FIG. 4 for the opened 30 carton C to be positioned on the slide table 66 without interference of the pusher brackets 105, the carton C can be opened and then the pusher brackets 105 and 105' advanced to the right to close the left bottom flap F of the 35 carton C and advance the carton C along the path X to the carton packer section. As the carton C is moved along the path X by the pusher brackets 105 and 105', the right bottom flap F of the carton C will also be folded inwardly with respect to the carton C into a horizontal position 40 as will be explained hereinafter.

Primary belt conveyor unit.—The primary conveyor unit 101 as seen in FIGS. 4, 16 and 20 receives the opened cartons C from the carton pusher 100, properly positions the carton under the carton packer section for the 45 containers to be placed in the carton, moves the loaded carton C along the path X to the partition inserter section, properly positions the carton C for the partitions to be inserted therein, and subsequently moves the loaded and partitioned carton C along the path X to the secondary conveyor 50 unit 102.

The primary conveyor unit 101 includes a carton lift arrangement 116 which positions the carton C so that the same can be loaded with containers from the carton packer section. A belt conveyor 118 extends longitudinally 55 under the carton packer and partition inserter sections and through the carton lift arrangement 116. It is effective to move the carton C along the path X. A first carton stop means 119 and a second carton stop means 120 are positioned adjacent the belt conveyor 118 under the partition 60 inserter section to selectively stop the carton C for the insertion of partitions therein.

The carton lift arrangement 116 received the carton C as the carton pusher 100 moves the opened carton C from the slide table 66. The arrangement 116 folds the flap F 65 on the right side of the carton C as shown in FIG. 4 as the pusher 100 moves the same and supports the same above the belt conveyor 118 while the containers are positioned therein. The carton lift arrangement 116 then lowers the loaded carton C onto the belt conveyor 118 70 which moves the carton C along the path X to the partition inserter section. The belt conveyor 118 operates continuously and will move the carton C therewith unless checked by the carton stop means 119 and 120.

As the loaded carton C is moved by the belt conveyor 75 118, the first stop means 119 is raised into interference

with the carton C. This checks the movement of the carton C along the path X in the proper position for the partition inserter section to place a first partition between the containers A in the carton C. The first stop means then lowers and the conveyor 118 continues to move the carton C along the path X.

The second stop means is now raised into interference with the carton C. This checks the movement of the carton C in proper position for the partition inserter section to place a second partition between the containers perpendicular to the first partition and in an interlocking relationship with the first partition. The second stop means then lowers and the belt conveyor 118 moves the carton C to the secondary conveyor 102.

Referring to FIGS. 4, 6, 7, 16 and 20, the belt conveyor 118 includes an endless flexible belt 121 carried by a plurality of rolls 122 and a driving roll 124. The belt 121 is considerably narrower than the width of the opened carton C so that the outer portions of the bottom of the carton C may be engaged by the lift arrangement 116 and the stop means 119 and 120 without interference with the belt 121. This allows the stop means 119 and 120 to check the movement of the carton C while the conveyor 118 operates continuously.

The rolls 122 and driving roll 124 are rotatably mounted between vertical support plates 125 carried between the side panels 14 and 15. The rolls 122 position the upper flight of the belt 121 horizontally so that the carton C resting thereon will be moved along the path X. The driving roll 124 is rotated by the bar conveyor 104, as will be explained later, to move the belt 121. The driving roll 124 rotates in such manner that the upper flight of the belt 121 moves from the left to the right as seen in FIGS. 4 and 16.

The carton lift arrangement 116 includes a pair of lift plates 126 and 126' positioned on each side of the belt conveyor 118. The lift plates 126 and 126' are maintained substantially parallel to the path X by vertical guide members 128 and 128' depending respectively downwardly from the lift plates 126 and 126'.

The guide assembly 112 slidably carries the guide members 128 and 128' between side walls 14 and 15 for vertical movement thereof as seen in FIG. 8. As the guide members 128 and 128' are slidably moved in the guide assembly 112, the lift plates 126 and 126' will selectively extend above or below the plane of the upper flight of the belt 121. Therefore, when the plates 126 and 126' extend above the plane of the upper flight of the belt 121, they will engage the bottom of the carton C transferred by the pusher 100 and support the carton C above the belt 121. On the other hand, when the lift plates 126 and 126' are lowered below the plane of the upper flight of the belt 121, the carton C carried by the lift plates 126 and 126' will be deposited on the belt 121 for transfer along the path X.

The guide members 128 and 128', and thus the plates 126 and 126', are maintained in horizontal alignment by a connecting rod 129 extending between the lower portions of the members 128 and 128'. The piston rod 130 of a fluid cylinder 131 carried by side wall 14 is connected to the connecting rod 129 through a bell crank arm 132. The bell crank 132 is pivoted to the guide assembly 112 so that extension of piston rod 130 as seen in FIG. 4 will raise the guide members 128 and 128'. This raises the lift plates 126 and 126' above the upper flight of belt 121. As the piston rod 130 is retracted, the lift plates 126 and 126' will be lowered below the upper flight of belt 121.

Those ends of the lift plates 126 and 126' facing the carton pusher 100 are wedge shaped as seen in FIG. 4. This provides inclined surfaces 134 which engage the right, or leading, bottom end flap F of the carton C as the carton pusher 100 moves the opened carton C along path X and folds the same under to a horizontal position. Now, both the leading and trailing bottom end flaps F are folded since the carton pusher 100 folds the trailing bottom end flap F.

As the carton pusher 100 transfers the opened carton C along the path X, the lift plates 126 and 126' are raised above the plane of the belt 121 so that the carton C rests thereon. The pusher 100 advances the carton C along the plates 126 and 126' sufficiently far to properly position the carton C under the carton packer section for loading with containers A.

The first stop means 119 as seen in FIGS. 16 and 17, engages and retains the carton C having the containers A therein in proper alignment with the first partition inserting means so that a first partition may be inserted between the containers A and the carton C. The first carton stop means 119 includes a pair of spaced L-shaped stop members 135 which are positioned on opposite sides of the belt 121 and which have vertical legs 136 selectively extendable above and below the plane of the upper flight of the belt 121. The L-shaped stop members 135 are fixedly mounted on the ends of a pivot shaft 138 rotatably extending through the vertical support plates 125 carrying the conveyor 118. A connecting link 139 is also fixedly attached to the pivot shaft 138 and extends downwardly therefrom. The connecting link 139 is pinned at its lowermost end to the extending end of a piston rod 140 of a fluid cylinder 141. The fluid cylinder 141 is pivotably mounted between the support plates 125 so that, as the piston rod 140 is retracting, the vertical legs 136 of the stop means 119 will be lowered below the plane of the belt 121 and when the piston rod 140 is extended, the vertical legs 136 will be raised above the plane of the belt 121 to check the movement of the carton C along the path X.

The second carton stop means 120 is identical in construction with the first stop means 119. It will be seen from FIG. 16, however, that the second stop means 120 is positioned so as to check the movement of the carton C, after having the first partition inserted between the containers A, in alignment with the second partition inserting means for the second partition to be inserted between the containers A. The second stop means 120 will not be described in detail, but will be indicated by primes of the reference numbers applied to the first stop means 119.

Secondary belt conveyor.—The secondary belt conveyor 102 receives the cartons C as they are discharged from the right end of the belt conveyor 118 as seen in FIG. 20 and moves the carton C to the right along the path X, as seen in FIG. 20. The secondary conveyor 102 is really a conveyor which transfers the loaded and partitioned carton C from the belt conveyor 118 to the bar conveyor 104. The secondary conveyor 102 includes a flexible belt 142 having a width substantially equal to flexible belt 121 of the conveyor 118, and has an upper flight in longitudinal and horizontal alignment with the upper flight of the flexible belt 121. The belt 142 is carried by a plurality of rolls 144 rotatably mounted between support plates 145 carried by the side panels 14 and 15. The belt 142 is driven by a drive roll 146 rotatably mounted between side panels 14 and 15 in such a manner that the upper flight of the belt 142 moves from the left to the right as seen in FIG. 20. The left end of the belt 142 is spaced from the right end of the belt 121 a sufficient distance for the bar conveyor 104 to pass therebetween. The drive roll 146 is driven by the bar conveyor 104 as will be explained hereinafter.

Bar conveyor.—The bar conveyor 104 engages the loaded and partitioned cartons C resting on the upper flight of belt 142 and transfers these cartons C through the flap folding section to fold the unfolded side bottom flaps F of the carton C. The bar conveyor 104 includes a pair of spaced parallel endless chains 148 carried by chain sprockets 149 rotatably mounted on the side panels 14 and 15. The sprockets 149 position the chains 148 so that one chain lies within a channel 143 carried by the front side panel 14 and the other chain lies within a channel 147 carried by the rear side panel 15 at the flap folding section. Transversely extending cross-bars 150 are connected between the chains 148 at spaced intervals therealong and

the upper flights of the chains 148 are positioned sufficiently far above the plane of the belt 142 for the cross-bars 150 to engage the trailing or left hand panel P of the carton C as seen in FIG. 20 and transfer the same through the flap folding section. The cross-bars 150 pass upwardly between the belts 142 and 121 to move into position behind the trailing end of the carton C. The chains 148 are synchronously driven by a drive unit 152 through a common shaft 151 carrying two of the lower sprockets 149. The drive unit 152 includes a conventional electric motor 154 connected to a transmission 155 which is in turn connected to the drive shaft 151 through a chain and sprocket arrangement 156.

Another of the sprockets 149 is drivingly connected to a transfer sprocket 157. The sprocket 157 is connected to the drive roll 146 of the secondary belt conveyor 102 by a chain 158. As the drive unit 152 drives the bar conveyor 104, the secondary belt conveyor 102 will also be driven.

A second transfer sprocket 153 is drivingly connected to one of the sprockets 149. The sprocket 153 is, in turn, connected to the driving roll 124 of the belt conveyor 118 by a chain 159. As the drive unit 152 drives the bar conveyor 104, the belt 121 of the conveyor 118 will also be driven.

CARTON PACKER SECTION

The carton packer section is positioned over the carton lift arrangement 116, and is effective to receive the containers A and properly position the containers A within the carton C for the partitions to be placed between the containers A and the carton C. For purposes of description, the carton packer section is divided into its three basic components: an infeed container conveyor 160, a drop table unit 161, and a lowering head assembly 162. The infeed container conveyor 160 receives the containers A from a conventional source (not shown) and presents the containers A to the drop table unit 161 in an ordered arrangement. The lowering head assembly 162 then engages the angle top configuration of the containers A, the drop table unit 161 collapses, and the lowering head assembly 162 lowers the containers A into the opened carton C.

Infeed container conveyor.—The infeed container conveyor 160 is mounted on the upper ends of the left standards 11, 11' and extends therefrom to the first intermediate upright supports 16, 16' as seen in FIGS. 1 and 4. The infeed conveyor 160 includes a pair of support channels 164 and 164', the support channel 164 extending between the left standard 11 and the first intermediate upright support 16 and the support channel 164' extending between the left standard 11' and the first intermediate upright support 16'.

An outer shaft 165 is rotatably mounted between the support channels 164 and 164' at the left end thereof seen in FIG. 4 and a drive shaft 166 is rotatably mounted between the support channels 164 and 164' adjacent the first intermediate upright supports 16 and 16'. It will be noted that the shafts 165 and 166 are horizontally oriented and extend substantially transversely of the path X along which the cartons C move. Idler sprockets 168 and 169 are mounted in spaced relationship on the shaft 165 and drive sprockets 170 and 171 are fixedly mounted in spaced relationship on the drive shaft 166. The idler sprocket 168 and the drive sprocket 170 are in alignment with each other and the idler sprocket 169 and the drive sprocket 171 are in alignment with each other. A metallic conveyor belt 172 extends around the drive sprocket 170 and the idler sprocket 168 and a metallic conveyor belt 174 extends around the drive sprocket 171 and the idler sprocket 169. It will be noted that the longitudinal centerline of the conveyor belts 172 and 174 are horizontally oriented parallel to the path X along which the cartons C pass through the machine.

The drive shaft 166 is selectively rotated through a chain and sprocket arrangement 175 shown in FIG. 4

by a conventional driving unit 176 as seen in FIG. 1. The driving unit 176 rotates the drive shaft 166 in such a manner that the upper flight of the conveyor belts 172 and 174 move from the left to the right as seen in FIG. 4. 5 Appropriate guides 178 are positioned in between the conveyor belts 172 and 174 to insure proper alignment of the containers A as they are moved along by the conveyor belts 172 and 174. The conveyor belts 172 and 174 are moved continuously by the driving unit 176 and a container lock-out assembly 179 selectively raises the containers A from the belts 172 and 174 to stop the feeding of the containers A.

The container lock-out assembly 179 includes a pair of lock-out members 180, one lock-out member 180 being positioned on one side of the conveyor belt 172 and the other lock-out member 180 being positioned on the opposite side of the conveyor belt 172. A pair of lock-out members 181 similar in construction to the lock-out members 180 are positioned on opposite sides of the conveyor belt 174. It will be noted that the width of a container A is sufficiently wider than the conveyor belts 172 and 174 to permit the lock-out members 180 and 181 to engage the bottoms thereof as the upper surface of the lock-out members 180 and 181 are raised 20 above the plane of the conveyor belts 172 and 174 to lift the containers A therefrom and check the forward movement of the containers A.

The lock-out members 180 and 181 are carried by left pivot links 182 and right pivot links 184, the left pivot links 182 being carried by a pivot shaft 185 and the right pivot links 184 being carried by pivot shaft 186. Each of the lock-out members 180 or 181 along with the pivot links 182 and 184 attached thereto define a parallelogram linkage so that the upper surface of the lock-out 35 members 180 and 181 will be maintained horizontally as they are raised and lowered above the plane of the upper flight of the conveyor belts 172 and 174.

The pivot shaft 186 has a depending driving link 188 extending therefrom and pinned to the extending end 40 of the piston rod 189 of fluid cylinder 190. The fluid cylinder 190 is mounted between the support channels 164 and 164' and the lock-out members 180 and 181 are raised above the plane of the conveyor belts 172 and 174 as the piston rod 189 is extended. Therefore, when 45 the containers A fed into the carton packer section engage a stop member 199, the piston rod 189 is extended thereby raising the lock-out members 180 and 181 to raise the containers A off the conveyor belts 171 and 174.

Drop table unit.—The drop table unit 161 as best seen in FIGS. 12-15 is mounted between the first intermediate upright supports 16 and 16' and the second intermediate supports 18 and 18' in horizontal alignment with the in-feed conveyor 160. The drop table unit 161 receives the containers A from the infeed conveyor 160 and positions the containers A in vertical alignment with the opened carton C resting on the carton lift arrangement 116. When the drop table unit 161 is collapsed, the containers A can be moved down into the opened carton C by the lowering head assembly 162 as seen in FIGS. 10 and 11.

The drop table unit 161 includes a pair of spaced support channels 191 and 191', the support channel 191 extending between the first intermediate upright support 16 and the second intermediate upright support 18 and the support channel 191' extending between the first intermediate support 16' and the second intermediate support 18'.

When the containers A are received by the drop table 70 unit 161, they rest on a parallel drop gates 192 and 194. The drop gates 192 and 194 are thin rectangular plates which have a length substantially equal to twice the width of the containers A and a width substantially equal to the width of the containers A. The drop gate 192 is fixed to a drop shaft 195. The drop shaft 195 is rotatably

mounted between cross struts 196 extending between the support channels 191 and 191'. It will be seen that the drop shaft 195 positions the drop gate 192 so that it lies in the same horizontal plane as the conveyor belt 172 and in alignment therewith. The drop gate 194 is fixedly mounted on a drop shaft 198 which is rotatably journaled between the struts 196 extending between the side channels 191 and 191'. The drop shaft 198 positions the drop gate 194 so that the upper surface thereof lies in the same horizontal plane as the conveyor belt 174 and is aligned therewith.

An adjustable check member 199 as seen in FIG. 4 is positioned adjacent the right end of the drop gates 192 and 194 and has a sufficient width to check the movement of the containers A as they are moved onto the drop gate 192 by the conveyor belt 172 and to check the movement of the containers A as they are moved onto the drop gate 194 by the conveyor belt 174. By appropriately adjusting the check member 199, the containers A moved onto the drop gates 192 and 194 will be properly aligned with the open carton C resting on the carton lift arrangement 116 thereunder.

When the lowering head assembly 162 engages the tops of the containers A and supports the same, the gates 192 and 194 will be pivoted downwardly and opened by the drop shafts 195 and 198 so that the containers A and the lowering head assembly 162 can pass between the drop gates 192 and 194 and lower the containers A down into the opened carton C. Conventional adjustable guides 200 as seen in FIG. 4 are positioned at the sides of the drop gates 192 and 194 to insure transverse alignment of the containers A with the carton C resting on the carton lift arrangement 116.

The drop gates 192 and 194 are positioned by a drop cylinder 201 which is pinned to the support channel 191' and has its piston rod 202 connected to the drop shaft 195 through a drop link 204. A conventional transfer linkage 205 connects the drop shaft 195 with the drop shaft 198 so that when the drop gate is pivoted downwardly, the drop gate 194 will also be pivoted downwardly synchronously therewith. Extension of the piston rod 202 pivots the gates 192 and 194 downwardly and retraction of the same pivots the gates 192 and 194 upwardly to a horizontal position for receipt of the containers A thereon.

The drop table unit 161 also includes a funnel assembly 210 mounted between the support channels 191 and 191' below and in alignment with the drop gates 192 and 194. The funnel assembly 210 comprises four (4) funnel gates 211 which are aligned with each other in their normal position to form a horizontal surface. The leading and trailing funnel gates indicated as 211a and 211b respectively in FIG. 14 are fixedly mounted on pivot shafts 212 which are in turn rotatably journaled between the support channels 193 and 193'. The side funnel gates indicated at 211c and 211d in FIG. 14 are fixedly mounted on pivot shafts 214 which are in turn rotatably journaled between cross struts 197 extending between the support channels 191 and 191'.

The funnel gates 211 are so positioned that when they are pivoted downwardly and outwardly by pivoting the shafts 212 and 214, the gates 211 will open and extend down and into the top of the open carton C to engage the top flaps F thereof. This causes the flaps F to be opened so that the containers A may be placed within the carton C by the lowering head assembly 162. Springs 215 are attached to the pivot shafts 212 and 214 so that the funnel gates 211 are always urged upwardly into their horizontal or closed position.

As the containers A are lowered between the drop gates 192 and 194, the bottom of the containers A engage the funnel gates 211 and force them downwardly and outwardly to open the top of the carton C and allow the containers A to be placed therein. After the containers A have been placed in the carton C, the lowering

head assembly 162 is retracted thereby allowing the funnel gates 211 to be pivoted back to their closed horizontal position by springs 215.

Lowering head assembly.—The lowering head assembly 162 is positioned above the drop table unit 161 and in vertical alignment therewith as seen in FIGS. 10 and 11. The lowering head assembly 162 is positioned sufficiently far above the drop table unit 161 so that the lowering head assembly, in its retracted position, is spaced above the containers A which rest on the drop gates 192 and 194. The assembly 162 is mounted between carriage beams 220 and 220', the carriage beam 220 extending between the upper end of intermediate upright supports 16, 18, and 19 while the carriage beam 220' extends between the intermediate upright supports 16', 18' and 19'.

The lowering head assembly 162 comprises generally a suction head 221 which is positioned above the containers A resting on the drop gates 192 and 194, a guide assembly 222 carried between the carriage beams 220 and 220', and a follower 224 connected to the suction head 221 and slidably received in the guide assembly 222 to maintain the lowering head 221 in vertical alignment with the guide assembly 222 while the containers A are being lowered into the carton C. A fluid cylinder 225 is vertically mounted on the guide assembly 222 and has its piston rod 226 attached to the suction head 221 so that as the piston rod 226 is extended, the suction head 221 will be lowered.

The suction head 221 is shaped to conform to the configuration of the top B of the containers A and includes a plurality of suction cups 228 which engage the angle tops B of the containers A to lower the containers A into the carton C. The suction cups 228 are selectively connected to the vacuum source VS through the vacuum line VL so that when the suction cups 228 are lowered into engagement with the angle tops B of the containers A, a vacuum is applied thereto so that the suction cups 228 support the containers A. At this time, the drop gates 192 and 194 are pivoted downwardly to open so that the suction head 221 can be lowered by extending the piston rod 226. This causes the bottom of the containers A to engage the funnel gates 211 and open the gates 211 downwardly and outwardly into the top of the carton C to open the top flaps F thereof as the suction head 221 continues to lower the containers A into the carton C.

To prevent the containers A resting on the conveyor belts 172 and 174 of the infeed conveyor from moving into the space presented thereto when the suction head 221 lowers the containers A pass the drop gates 192 and 194, a back-up plate 229 is provided along that side of the follower 224 which faces the containers A on the conveyor belts 172 and 174. This prevents the containers A from moving into the space normally occupied by the drop gates 192 and 194 until the suction head 221 has been fully retracted by the piston rod 226.

The carton C is maintained in proper position under the lowering head assembly by the carton lift arrangement 116 and by guide rails 223, as seen in FIG. 4. The lift arrangement 116 supports the carton C above the belt conveyor 118 and the guide rails 223 maintain the carton C centered transversely of the path X along which the cartons are moved. After the containers have been placed in the cartons C, the lift arrangement 116 lowers the carton onto the belt conveyor 118 for movement to the partition inserter section.

PARTITION INSERTER SECTION

Referring specifically to FIGS. 16-19, the partition inserter section comprises generally a first partition inserter 240 and a second partition inserter 241. The first partition inserter 240 is effective to position a first partition D between the containers A in the carton C in alignment with the path X along which the cartons C pass. The partition inserter 241 is effective to position a second partition E between the containers A transversely of

the path X so that the partitions D and E are in an interlocking position. It will be noted from FIG. 1, that the first partition D has an upwardly opening slot D' therein while the second partition E has a downwardly opening slot E' therein. As the partitions D and E are positioned together, the slot E' receives the partition D therein while the slot D' receives the partition E therein so that the partitions D and E are in an interlocking position to maintain the containers A properly located within the carton C.

The second partition inserter 241 is identical in construction to the first partition inserter 240, the partition inserters being rotated 90° with respect to each other. Therefore, the partition inserter 240 will be described in detail while primes of the reference numerals applied to the partition inserter 240 will be applied to corresponding parts of the partition inserter 241.

The first partition inserter 240 comprises generally a partition magazine 242 and an inserter assembly 244. The magazine 242 is effective to receive the first partitions D and maintain the partitions D in a vertical position until the inserter assembly 244 places the partitions D one at a time between the containers A in the carton C when the carton C is stopped at the first partition inserting station by the stop means 119 in the conveyor section.

The partition magazine 242 is similar in construction to the magazine 20 and includes a pair of spaced apart slide rails 245 upon which the partitions D rest and a weighted driving unit 246 which force the partitions D down the slide rails 245 toward the inserter assembly 244. The slide rails 245 are inclined downwardly toward the inserter assembly 244 so that the force of gravity on the driving assembly 246 constantly forces the partitions D toward the inserter assembly 244.

The inserter assembly 244 is mounted between the carriage beams 220 and 220' and includes a check assembly 249 carried by a support beam 243 and to which the magazine 242 is connected. The check assembly 249 includes a pair of spaced apart vertical check plates 250 which are positioned at the front of the magazine 242 and serve to arrest the forward movement of the partitions D therein.

A partition stripper plate 251 is positioned between the check plates 250 for vertical movement between the check plates 250 to strip the first partition D in the magazine 242 from the magazine and into the carton C under the partition inserter 240. The stripper plate 251 is carried on the downwardly extending end of a piston rod 252 of a vertically mounted fluid cylinder 254.

The fluid cylinder 254 is carried by a guide assembly 255 mounted between carriage beams 220 and 220'. A follower 256 is attached to the stripper plate 251 to maintain the stripper plate 251 properly aligned between the check plates 250 as the piston rod 252 lowers and raises the stripper plate 251. The stripper plate 251 has a configuration such that only the first partition D in the magazine 242 is engaged thereby and lowered past the check plates 250 and into the open top of the carton C between the containers A.

A pair of guide members 258 are mounted at the lower ends of the check assembly 249 and are mounted on pivot shafts 259 so that each of the guide members 258 may be pivoted from a horizontal closed position to a vertical open position. Each of the guide members 258 has a U-shaped cross-section to define a guide slot 260 therein through which the partitions D pass as they are being lowered into the open carton C. It will thus be seen that the guide members 258 are positioned along each side edge of the partition D to properly guide the partition D into the open carton C between the containers A.

A fluid cylinder 251 pivotally mounted on the check assembly 249 as seen in FIG. 19 has its piston rod 252 connected through an appropriate linkage to one of the pivot shafts 259 and a connecting rod 264 connects the two pivot shafts 259 together. As the piston rod 252 is re-

tracted, both of the guide members 258 will be pivoted from a horizontal closed position to a vertical open position to guide the partition D into the carton C. The guide members 258 further serve the purpose of opening the leading and trailing upper end flaps F of the carton C so that the partition may be easily inserted within the carton C. The operation of the fluid cylinder 261 is effective to pivot the guide members 258 downwardly just as the stripper plate 251 starts its downward stroke to properly guide the partition D while not interfering with the movement of the carton C along the path X.

The carton C having the containers A therein is properly oriented under the first partition inserter 240 by the first stop means 119 in conjunction with a guide rail 248 extending through the partition inserter section. The stop means 119 checks the movement of the carton C longitudinally along the path X while the guide rail 248 positions the carton C transversely of the path X.

The carton C is properly oriented under the second partition inserter 240 by the second stop means 120 in conjunction with the guide rail 248. The stop means 120 positions the carton C longitudinally along the path X while the guide rail 248 positions the carton C transversely of the path X.

The partition inserter 241 operates in identically the same manner as the partition inserter 240 except that the partition inserter 241 is turned transversely of the partition inserter 240 and the partition E is inserted in place of the partition D. It will also be noted that the partition D and the partition E are identical, the only difference lying in the fact that the partitions E are rotated 180° with respect to the partitions D when they are inserted into the magazine 242'. After the partitions are inserted into the carton C, the carton C is moved out of the partition inserter section and into the flap folding section by the belt conveyor 118.

FLAP FOLDING SECTION

The flap folding section is effective to fold the side bottom flaps F of the carton C to prepare the carton for sealing. The carton C is engaged by the bar conveyor 104 and moved through the flap folding section.

The flap folding section includes a slide plate 270 on which the carton C rests as the flaps F are being folded and a pair of contoured folding members 271 which engage the bottom side flaps F and fold them. The slide plate 270 is a thin, flat, horizontally oriented member positioned at the end of the secondary belt conveyor 102 and extends between the folding members 271. The folding members 271 are so contoured that the unfolded flaps F are folded up and under the slide plate 270. As the carton C moves from the slide plate 270, the members 271 finish folding the flaps F into juxtaposition with the already folded leading and trailing bottom flaps F and the carton C is discharged ready for sealing.

CONTROL SYSTEM

The machine is controlled by a pneumatic system, the main valves as shown in FIGS. 23-25 being disclosed as follows:

MANUAL CONTROL VALVES

MV—Main valve for system.

Carton opener section

PB-1—Main valve for opener section control.
PB-2—Start valve for automatic operation of machine.
MV-1—Main valve to cylinders in opener section.
MV-2—Main valve for vacuum control the opener arm 79.

Carton packer section

PB-11—Main valve for carton packer control.
PB-12—Reset valve to reset carton packer section.
MV-11—Main valve to cylinders in packer section.

Partition inserter section

PB-21—Main valve for partition inserter control.
 PB-22—Reset valve to reset partition inserter section.
 MV-21—Main valve to cylinders in inserter section.

LIMIT CONTROL VALVES

Carton opener section

LV-1—In series with LV-3, moves carton stripper plate 58 up; located adjacent stripper follower 65.

LV-2—In series with LV-5, controls vacuum to opener arm suction cups 98; located below opener arm 79.

LV-3—Controls stabilizer 68 and, in series with LV-1, moves stripper plate 58 up; located below opener arm 79.

LV-4—In series with LV-6, controls feed stroke of carton pusher 100 and raises lift plates 126 and 126'; located on positioning bar 105 in carton opener section.

LV-5—Controls forward pivoting of opener arm 79 and, in series with LV-2, controls vacuum to suction cups 98; located under opener arm.

LV-6—In series with LV-4, controls feed stroke of carton pusher 100 and raises lift plates 126 and 126'; located on guide rail 223 in carton packer section.

LV-7—Controls return stroke of carton pusher 100 in series with LV-9, moves stripper plate 58 down in series with LV-8, and moves opener arm 79' in; located below opener arm 79.

LV-8—Controls down stroke of stripper plate 58 in series with LV-7; located below carton stripper.

LV-9—Controls return stroke of carton pusher 100 in series with LV-7; located below opener arm 79.

Carton packer section

LV-10—Controls lowering of lift plates 126 and 126'; located on inserter guide rail 223.

LV-11—Controls closing of drop gates 192 and 194; located on guide assembly 222.

LV-12—Controls vacuum and lowering of suction head 221 and raises container lock-out assembly 179 in series with LV-17, LV-18, and LV-13; located on stop member 199.

LV-13—Controls vacuum and lowering of suction head 221 and raises container lock-out assembly 179 in series with LV-12, LV-17 and LV-18; located on stop member 199.

LV-14—Controls opening of drop gates 192 and 194 in series with LV-17, LV-18, LV-12 and LV-13; located on guide assembly 222 adjacent follower 224.

LV-17—Controls lowering head assembly vacuum and down stroke in series with LV-18, LV-12 and LV-13, resets relay valve RV-10, and in series with LV-18 transfers relay valve RV-10; located on guide assembly 222 adjacent follower 224.

LV-18—Controls lowering head assembly down stroke in series with LV-12, LV-13 and LV-17, and in series with LV-17, transfers relay valve RV-10; located on packer guide rail 223.

Partition inserter section

LV-20—Controls up and down stroke of partition inserter 240 as well as resets relay valve RV-22 in series with LV-22; transfers relay valve RV-22.

LV-22—Resets relay valve RV-23, controls the opening of guide members 258, and controls upward pivotal movement of first stop means 119; located on guide assembly 255 adjacent follower 256.

LV-21—Transfers relay valve RV-23; located on follower 256.

LV-22—Controls movement of stripper plate 251 in partition stripping unit 248 in series with LV-20 and activates relay valve RV-22; located adjacent follower 256.

LV-23—Controls downward pivotal movement of first stop means 119; located on inserter guide rail 223.

LV-24—Controls up and down stroke of second partition inserter 241 and resets relay valve RV-21 in series with LV-26; controls upward pivotal movement of second stop means 120 and transfers relay valve RV-21; located on inserter guide rail 223.

LV-25—Controls downward pivotal movement of second stop means 120 and closes guide members 258; located on follower 256' of second partition inserter 241.

LV-26—Controls movement of stripper plate 251' of the second partition inserter 241 and activates relay valve RV-21 in series with LV-24; located on follower 256' of the second partition inserter 241'.

RELAY VALVES

RV-10—Located in carton packer section and reset as air is supplied to air solenoid RV-10A when passage valve 17A of valve LV-17 is passing, transferred as air is supplied to air solenoid RV-10B when passage valve 17B of valve LV-17 and passage valve 18A of valve LV-18 are passing simultaneously; includes the following passage valves: RV10-1, normally not passing, and RV10-2, normally passing; the passage valve RV10-1 is transferred to a passing state and passage valve RV10-2 transferred to a not-passing state when air solenoid RV-10B is activated and reset back again when air solenoid RV-10A is activated, passage valve RV10-1 controls the vacuum and the downstroke of the lowering head assembly 162 in series with LV-17, LV-18, LV-12 and LV-13 and passage valve RV10-2 controls the lowering of lift plates 126 and 126' in series with LV-10.

RV-21—Located in partition inserter section and reset as air is supplied to air solenoid RV-21A before PB-21 is transferred or when passage valve 24A of valve LV-24 and passage valve 26A of valve LV-26 as well as passage valve RV-21-1 are passing, and transferred as air is supplied to air solenoid RV-21B when passage valve 24B of valve LV-24 is passing and passage valve RV21-2 is passing; includes the following passage valves: RV21-1, normally not passing, and RV21-2, normally passing; the passage valve RV21-1 is transferred to a passing state and passage valve RV21-2 is transferred to a not-passing state when air solenoid RV-21B is activated and reset back again when air solenoid RV-21A is activated; passage valve RV21-1 controls the stripper plate 251' of the second partition inserter 241 and activates relay valve RV-21 in series with valves LV-24 and LV-26 while passage valve RV21-2 pivots the second stop means 120 up and transfers relay valve RV-21 in series with passage valve 24B of valve LV-24.

RV-22—Located in partition inserter section and reset as air is supplied to air solenoid RV-22A before PB-21 is transferred or when passage valves 20A of valve LV-20 and 22A of valve LV-22 as well as passage valve RV22-1 are passing, and transferred as air is supplied to air solenoid RV-22B when passage valve 20B of valve LV-20 and passage valve RV23-2 are passing; includes passage valve RV22-1, normally not passing and passage valve RV22-2, normally passing; the passage valve RV22-1 is transferred to a passing state and passage valve RV22-2 is transferred to a not-passing state when air solenoid RV-22B is activated and reset back when air solenoid RV-22A is activated; passage valve RV22-1 in series with LV-20 and LV-22 controls the movement of stripper plate 251 of the first partition inserter 240, while passage valve RV22-2 transfers relay valve RV-22 and resets relay valve RV-23 before PB-21 is transferred.

RV-23—Located in partition inserter section and reset as air is supplied to air solenoid RV-23A before PB-21 is transferred or when passage valve 20B of valve LV-20 and passage valve RV22-2 of relay valve RV-22 are passing, and transferred as air is supplied to air solenoid RV-23B when LV-21 is passing; includes passage valve RV23-1, normally not passing, and passage valve RV23-2, normally passing; the passage valve RV23-1 is transferred to a passing state and valve RV23-2 transferred to a not-

passing state when air solenoid RV-23B is activated and reset when air solenoid RV-23A is activated; passage valve RV23-1 controls the closing of guide members 258 and, in series with LV-23, pivots first stop means 119 down while passage valve RV23-2, in series with passage valve 20B of LV-20, activates air solenoid RV-22B.

PILOT OPERATED VALVES

PV-1—Controls position of stabilizer 68, extends suction cups 75 when pilot PV-1A is activated by LV-3, retracts suction cups 75 when pilot PV-1B is activated by LV-3.

PV-2—Controls carton stripper 21, moves stripper plate 58 down when pilot PV-2B is activated by LV-7 and LV-8 in series, moves stripper plate 58 up when pilot PV-2A is activated by LV-3 and LV-1 in series.

PV-3—Controls opener arm 79 movement, moves arm 79 in when pilot PV-3B is activated by LV-7, moves arm 79 out when pilot PV-3A is activated by LV-5.

PV-4—Controls carton pusher 100, generates feed stroke when pilot PV-4B is activated by PB-2 in series with LV-6 or by LV-4 in series with LV-6, generates return stroke when pilot PV-4A is activated by LV-7 in series with LV-9.

PV-5—Controls vacuum to opener arm suction cups 98, vacuum off when pilot PV-5B is activated by LV-5 in series with LV-2, vacuum on when pilot PV-5A is activated by LV-5, LV-2 and MV-2 in series.

PV-6—Controls vacuum to stabilizer suction cups 75, vacuum off when pilot PV-6B is activated by LV-3, vacuum on when pilot PV-6A is activated by LV-3.

PV-12—Controls vacuum to carton packer suction cups 228, vacuum off when pilot PV-12B is activated by LV-17, vacuum on when pilot PV-12A is activated by LV-17, LV-18, RV10-1, LV-12 and LV-13 in series.

PV-13—Controls movement of carton packer suction head 221, generates loading stroke when pilot PV-13B is activated by LV-17, LV-18, RV10-1, LV-12 and LV-13 in series, generates return stroke when pilot PV-13A is activated by LV-17.

PV-14—Controls movement of container lockout members 180 and 181, moves them up when pilot PV-14B is activated by LV-17, LV-18, RV10-1, LV-12 and LV-13 in series, moves them down when pilot PV-14A is activated by LV-15.

PV-15—Controls movement of drop gates 192 and 194, gates open when pilot P-15B is activated by LV-17, LV-18, RV10-1, LV-12, LV-13 and LV-14 in series, gates close when pilot PV-15A is activated by LV-11 or PB-12.

PV-16—Controls lift plates 126 and 126', plates move up when pilot PV-16B is activated by PB-2 in series with LV-6 or by LV-4 in series with LV-6, plates move down when pilot PV-16A is activated by RV10-2 in series with LV-10.

PV-21—Controls second partition inserter stripper plate 251', moves plate down when pilot PV-21B is activated by LV-24, RV21-1 and LV-26 in series, moves plate up and when pilot PV-21A is activated by LV-24, RV21-1 and LV-26 in series.

PV-22—Controls second stop means 120, lowers stop means when pilot PV-22B is activated by LV-25, raises stop means when pilot PV-22A is activated by LV-24.

PV-23—Controls first partition inserter stripper plate 251, moves plate down when pilot PV-23B is activated by LV-20, RV22-1 and LV-22 in series, moves plate up when pilot PV-23A is activated by LV-20, RV22-1 and LV-22 in series.

PV-24—Controls first stop means 119, lowers stop means when pilot PV-24B is activated by RV23-1 and LV-23 in series, raises stop means when pilot PV-24A is activated by LV-20.

PV-25—Controls second partition inserter guide members 258', closes members when pilot PV-25B is activated

by LV-25, opens members when pilot PV-25A is activated by LV-24 in series with RV21-1.

PV-26—Controls first partition inserter guide members 258, closes members when pilot PV-26B is activated by RV23-1, opens members when pilot PV-26A is activated by LV-20 in series with RV22-1.

The manual control valves MV, MV-1, MV-2, MV-11, and MV-21 are all two position spool valves manually operated to control the position of the spool in the valve. The manual control valves PB-1, PB-11 and PB-21 are all two position, push-pull type pneumatic valves having a first position in which the control circuitry for each section is connected to the fluid pressure line PL to ready the machine for automatic operation. Each of the valves have a second position which connect up that portion of the circuitry of the machine for automatic operation thereof. The manual control valves PB-2, PB-12, and PB-22, are all momentarily engaged fluid valves normally sprung urged to a not passing position. The valve PB-2 starts the automatic operation of the machine when momentarily closed by causing the case pusher 100 to complete its feed stroke. The valve PB-12 serves as a reset valve for resetting the carton packer section of the machine and the valve PB-22 serves a similar function to reset the partition inserter section of the machine.

The limit control valves are conventional pneumatic limit valves which are opened and closed in response to the movement of a wand attached thereto.

Limit valve LV-1 is a single passage valve which is normally not passing. It is transferred to a passing position by a cam on the carton stripper follower 65 when the stripping plate 58 has completed its downward stripping stroke to move a carton C from the magazine 20 into carton opening position.

Limit valve LV-2 is two passage valve having a first passage valve LV-2A which is normally not passing and a second passage valve LV-2B which is normally passing. The valve LV-2 is a push type valve and is transferred when the open arm 79 moves in.

Limit valve LV-3 is two passage push type limit valve having a first passage valve 3A and a second passage valve 3B, the first passage valve 3A being normally passing and the second passage valve 3B normally not passing. It is transferred just as the open arm 79 starts moving out.

Limit valve LV-20 is a two-passage valve having a first mally not passing. The limit valve LV-4 is transferred when an opened carton C has been moved in position for the carton pusher 100 to feed.

Limit valve LV-5 is a two-passage valve having a first passage valve 5A which is normally not passing and a second passage valve 5B which is normally passing. Limit valve LV-5 is transferred on the return stroke of the carton pusher 100 and reset on the feed stroke of the carton pusher 100.

Limit valve LV-6 is a single passage normally passing valve. Valve LV-6 is transferred when a carton C is in the loading station under the carton packer section of the machine.

Limit valve LV-7 is a single passage valve which is normally not passing. Valve LV-7 is transferred on the feed stroke of the carton pusher 100.

Limit valve LV-8 is a single passage valve which is normally passing. Limit valve LV-8 is transferred when a carton C has been stripped from the magazine 20 into carton opening position.

Limit valve LV-9 is a single passage valve which is normally not passing. Limit valve LV-9 is a push type valve and is transferred by the opener arm 79 when it is moved to its innermost position.

Limit valve LV-10 is a single passage valve normally passing. Valve LV-10 is transferred when a carton C is in position under the first partition inserter 240 in the partition inserter section.

Limit valve LV-11 is a single passage valve normally

not passing. Valve LV-11 is transferred on the return stroke of the lowering head assembly 62.

Limit valve LV-12 is a single passage valve which is normally not passing. Valve LV-12 is a push type valve and transferred when those containers A carried by the conveyor belt 172 have moved into position under the lowering head assembly 162.

Limit valve LV-13 is a single passage valve which is normally not passing. Valve LV-13 is a push type valve and transferred when the containers A on the conveyor belt 174 have moved into position under the lowering head assembly 162.

Limit valve LV-14 is a single passage valve which is normally not passing. Valve LV-14 is transferred on the down stroke or loading stroke of the lowering head assembly 162.

Limit valve LV-17 is a two-passage valve having a first passage valve 17A which is normally not passing and a second passing valve 17B which is normally passing. Valve LV-17 is transferred when the lowering head assembly 162 has completed its down or loading stroke.

Limit valve LV-18 is a two-passage valve having a first passage valve 18A which is normally passing and a second passage valve 18B which is normally not passing. Valve LV-18 is transferred when an opened carton C is in the loading station under the lowering head assembly 162.

Limit valve LV-20 is a two-passage valve having a first passage valve 20A which is normally not passing and a second passage valve 20B which is normally passing. Valve LV-20 is transferred when a carton C is in position under the first partition inserter 240 in the partition inserter section.

Limit valve LV-21 is a single passage valve which is normally not passing. Valve LV-21 is transferred as the first partition inserter 240 is performing its up or return stroke.

Limit valve LV-22 is a two passage valve having a first passage valve 22A which is normally not passing and a second passage valve 22B which is normally passing. Valve LV-22 is transferred when the first partition inserter 240 has completed its down or loading stroke.

Limit valve LV-23 is a single passage valve which is normally passing. Valve LV-23 is transferred when a carton C is in position under the second partition inserter 241 in the partition inserter section.

Limit valve LV-24 is a two-passage valve having a first passage valve 24A and a second passage valve 24B. Valve LV-24 is transferred when the carton C is in place under the second partition inserter 241 in the partition inserter section.

Limit valve LV-25 is in a single passage valve which is normally not passing. Valve LV-25 is transferred during the up or return stroke of the second partition inserter 241.

Limit valve LV-26 is a two-passage valve having a first passage valve 26A which is normally not passing and a second passage valve 26B which is normally passing. Valve LV-26 is transferred when the second partition inserter 241 has completed its down stroke.

OPERATION

From the foregoing description, it will be seen that the operation of the machine is started by loading the carton magazine 20 with cartons C in a flat collapsed condition, loading the first partition inserter magazine 242 with first partitions D and loading the second partition inserter magazine 242' with second partitions E. The manual control valves MV, MV-1, MV-11, and MV-21 are transferred to a passing state so that fluid under pressure will be supplied through the pressure line PL from the pressure source PS to the cylinders of the machine. At this time, pressure will be supplied from pressure line PL through manual control valve PB-1 in its first position to pilots PV-2A and PV-4A to cause pilot valves PV-2 and PV-4 to supply air from pressure

line PL respectively to the fluid cylinder 60 of the carton stripper 21 and the fluid cylinder 114 of the carton pusher 100 to cause the stripping plate 58 of the carton stripper 21 to move to its up position and cause the pusher brackets 105 and 105' to complete their return stroke of movement toward the left as seen in FIG. 4.

Also, air will be supplied from pressure line PL through manual control valve PB-11 in its first position to pilot PV-12B of pilot valve PV-12, to pilot PV-13A of pilot valve PV-13, to air solenoid RV-10A of relay valve RV-10 and to pilot PV-14B of pilot valve PV-14. Pilot valve PV-12 cuts off the vacuum to the section cups 228 on the suction head 221 while the pilot valve PV-13 supplies air to fluid cylinder 225 and the lowering head assembly 62 to return the suction head 221 to its uppermost position. Supplying air to relay valve RV-10 through air solenoid RV-10A causes the relay valve RV-10 to be reset so that passage valve RV-10-2 is rendered passing. Pilot valve PV-14 supplies air to fluid cylinder 190 in the container lockout 179 to move the lockout members 180 and 181 to their uppermost position above the level of the upper flight of belts 172 and 174.

Air from pressure line PL is supplied through manual control valve PB-21 in its first position to air solenoid RV-21A of relay valve RV-21, to pilot PV-21A of pilot valve PV-21, to air solenoid RV-22A of relay valve RV-22, to pilot PV-23A of pilot valve PV-23, to air solenoid RV-22B of relay valve RV-22, to air solenoid RV-23A of relay valve PV-23, and to pilot PV-24A of pilot valve PV-24. This is effective to transfer relay valve RV-21 and to supply air to fluid cylinder 141' in the second stop means 120 to raise the member 136' above the upper flight of belt 121. Relay valve RV-22 is reset and pilot valve PV-23 supplies air to fluid cylinder 254 in the first partition inserter 240 to move the stripping plate 251 to its uppermost position. Also, relay valve RV-22 is transferred and relay valve RV-23 is reset while pilot valve PV-24 is effective to supply air to fluid cylinder 141 in the first stop means 119 to raise the stop member 136 above the plane of the upper flight of belt 121.

To start automatic operation of the machine, the manual control valves PB-1, PB-11, and PB-21 are all transferred to their second position. Then valve PB-2 is momentarily depressed to by-pass limit valve LV-4 and activate pilots PV-4B and PV-16B through limit valve LV-6. This is effective to cause pilot valve PB-4 to supply air to fluid cylinder 114 and cause the carton pusher 100 to feed. This moves the pusher brackets 105 and 105' to the right as seen in FIG. 4. Also, pilot valve PV-16 supplies air to fluid cylinder 131 in the carton lift arrangement 116 to raise the lift plates 126 and 126'.

When the feed stroke of the carton pusher 100 is completed, limit valve LV-7 is transferred to a passing condition to activate pilot PV-3B and pilot PV-2B through normally passing limit valve LV-8. This causes pilot valve PV-2 to supply air to fluid cylinder 60 in the carton stripper 21 to move the stripping plate 58 down to strip a carton C from the magazine 20 in front of the undercarriage 30 and the suction cups 75 of the stabilizer 68 into carton opening position. At this point the carton C rests on the rear portion 66A of the slide table 66. Pilot valve PV-3 supplies air to fluid cylinder 92 of the carton opening assembly 78 to move the opener arm 79 rearwardly into the machine into engagement with the front of the carton C resting on the slide table 66.

As the carton stripper 21 completes its down stroke, limit valve LV-1 and limit valve LV-8 are transferred. As the opener arm 79 moves to its innermost position, limit valve LV-3 is also transferred. At this point, air is supplied to pilots PV-1A and PV-6A through passage valve 3B of limit valve LV-3. Pilot valve PV-1 supplies air to fluid cylinder 71 in the stabilizer 68 to cause the suction cups 75 to be moved forwardly into engagement

with the rear panel P of the carton C resting on the slide table 66. At the same time air is supplied to the fluid cylinder 41 of the alignment mechanism 38 to move the wedge member 39 thereof forwardly to cause the cartons C in the magazine 20 to be shifted at their lower portions to align them into position behind the follower 65 of the carton stripper 21. Pilot valve PV-6 supplies a vacuum to the vacuum cups 75 of the stabilizer 68 to cause the rear side panel P of the stripped cartons C to be engaged thereby.

Also, when the opener arm 79 has moved to its innermost position, limit valve LV-2 will be transferred so that passage valve 2A thereof supplies air to pilot PV-5A. This causes pilot valve PV-5 to supply a vacuum to the suction cups 98 of the carton opening assembly 78 so that the front panel P of the carton C will be engaged thereby.

When the opener arm 79 has moved to its innermost position, limit valve LV-9 is also transferred so that the carton pusher 100 initiates its return stroke to move the pusher brackets 105 and 105' to the left as seen in FIG. 4. When the carton pusher 100 completes its return stroke, limit valve LV-5 is transferred so that passage valve 5A supplies air to pilot PV-3A. This is effective to reset limit valve LV-7 to its not passing state also. Pilot valve PV-3 supplies air to fluid cylinder 92 of the carton opening assembly 78 so that the opener arm 79 is moved forwardly out of the machine. Since the front panel P of the stripped carton C is engaged by the suction cups 98 thereof, the front panel P of the carton C is moved outwardly with the opener arm 79. As soon as the opener arm has moved a small predetermined amount outwardly, limit valve LV-3 is reset so that passage valve 3A thereof supplies air to pilot PV-2A through limit valve LV-1 and to pilot PV-1B as well as pilot PV-6B. This is effective to cause pilot valve PV-2 to supply air to fluid cylinder 60 of the carton stripper 21 and move the stripping plate 58 thereof up for the next stripping operation. Pilot valve PV-1B supplies air to fluid cylinder 71 of the stabilizer 68 to cause the same to retract the suction cups 75 thereof and supply air to the fluid cylinder 41 of the alignment mechanism 38 to retract the wedge member 39 thereof. Pilot valve PV-6B is effective to cut off the vacuum supplied to the suction cups 75 simultaneously with the retraction of the cups 75 so as to release the rear panel P of the carton C. This is effective to cause the panels P of the carton C to be broken apart to initiate the opening operation. As the opener arm 79 continues to move forwardly out of the machine, the deflector 102 completes the setting up of carton C in an opened condition.

As soon as the opened carton C is in position, limit valve LV-4 is transferred to supply air through limit valve LV-6 to pilots PV-4B and PV-16B to cause the carton pusher 100 to feed and the lift arrangement 116 to move the lift plates 126 and 126' above the level of the belt 121. As soon as the carton pusher 100 starts its feed stroke, limit valve LV-5 is reset so that passage valve 5B thereof supplies air through passage valve 2A of limit valve LV-2, reset when the opener arm 79 moved out, to pilot PV-5B to cause pilot valve PV-5 to cut off the vacuum from the opener suction cups 98.

As the carton pusher 100 completes its feed stroke, the leading and trailing bottom end flaps F of the carton C are folded inwardly into a horizontal position and the opened carton C is now in position on the lift plates 126 and 126' within the carton packer section of the machine ready for loading. This transfers limit valve LV-6 to prevent the next carton C that has been stripped from the magazine 20 and opened by the opening assembly 78 from being fed into the carton packer section until the carton C already in the carton packer section has been transferred therefrom into the partition inserter section.

When the carton C has been transferred into the carton packer section, limit valve LV-18 is transferred. Also, the

containers A on the carton infeed conveyor have been moved onto the drop table unit 161 and have engaged the check member 199 thereof. This was effective to transfer limit valves LV-12 and LV-13. Therefore, as soon as limit valve LV-18 is transferred, pilots PV-12A and PV-13B as well as pilot PV-14B are activated. This causes pilot valve PV-12 to turn on the vacuum to suction cups 228 of the lowering head assembly 62 and to cause the pilot valve PV-13 to supply air to fluid cylinder 225 of the lowering head assembly 62 to start downward movement of the suction head 221. Pilot valve PV-14 is effective to supply air to the fluid cylinder 190 of the lockout assembly 179 and raise the lockout members 180 and 181. This lifts the containers A on the conveyor belt 172 and 174 to prevent feeding of the containers A during the loading of the carton C.

As soon as the suction cups 228 on the suction head 221 engage the angle tops B of the containers A, limit valve LV-14 is transferred to activate pilot PV-15B. Pilot valve PV-15 is effective to supply air to fluid cylinder 201 of the drop gate unit 161 to open the gates 192 and 194 so that the containers A will be held solely by the suction head 221 and can be moved between the gates 192 and 194. As the suction head 221 continues to lower the containers A, the bottoms of the containers A engage the funnel gates 211 and force them downwardly and outwardly to open them and spread the upper flaps F of the carton C. The suction head 221 continues to move the containers A down into the carton C to load the same.

When the suction head 221 completes its down loading stroke, limit valve LV-17 is transferred so that air is supplied through passage valve 17A to air solenoid RV-10A, pilot PV-12B and pilot PV-13A. Pilot valve PV-12 turns the vacuum off to the suction cups 228 and pilot valve PV-13 supplies air to the fluid cylinder 225 of the lowering head assembly 62 to retract the same and raise the suction head 221. Passage valve RV10-2 of relay valve RV-10 supplies air to pilot PV-16A through limit valve LV-10 so that pilot valve PV-16 supplies air to fluid cylinder 131 of the carton lift arrangement 116 to lower the lift plates 126 and 126' This lowers the loaded carton C onto the belt 121 for movement into the partition inserter section of the machine.

When the suction head 221 has been returned, limit valve LV-11 is transferred to activate pilot PV-15A. This causes pilot valve PV-15 to supply air to fluid cylinder 201 and raise the gates 192 and 194 to a closed position. By this time, limit valves LV-12, LV-13, LV-14, LV-17, and LV-18 have been reset.

The belt conveyor 121 continues to move the loaded carton C along the path X through the machine until the first stop means 119, which is in its raised position, engages the carton C and arrests the movement thereof. At this time, limit valves LV-10 and LV-20 are transferred. When limit valve LV-10 is transferred, the carton lift arrangement 116 will not be lowered to deposit a carton C in the carton packer section onto belt 121 while a carton C is in position under the first partition inserter 240 in the partition inserter section. When limit valve LV-20 is transferred, the passage valve 20A thereof supplies air through the now closed passage valve RV22-1 to pilot PV-23B and pilot PV-26A. Pilot valve PV-23 is effective to supply air to fluid cylinder 254 of the first partition inserter 240 to move the stripper plate 251 and a partition D down into the carton C between the containers A. Pilot valve PV-26 is effective to supply air to fluid cylinder 261 and pivot the guide members 258 down into their open position. The stripper plate 251 moves the partition D from the magazine 242 down into the carton C between the containers A and in alignment with the path X through the machine.

When the first partition inserter 241 completes its down stroke, limit valve LV-22 is transferred so that passage valve 22A supplies air to air solenoid RV-22A and pilot valve PV-23A. This causes relay valve RV-22 to be reset and

causes pilot valve PV-23 to supply air to the cylinder 254 and raise the stripping plate 251.

As stripping plate 251 starts its upward stroke, limit valve LV-21 is transferred to supply air to air solenoid RV-22B to transfer passage valve RV23-1 to a passing state thereby activating pilot PV-24B and PV-26B. Pilot valve PV-24 is effective to supply air to the fluid cylinder 141 of the first stop means 119 to lower the stop members 136 thereof. Pilot valve PV-26 is effective to supply air to fluid cylinder 261 to raise the guide members 258 and close the same. When the stop members 136 are lowered, the belt 121 moves the carton with the first partition D therein along the path X through the machine until the carton is engaged by the stop members 136' of the second stop means 120.

When the carton C is under the second partition inserter 241, the limit valves LV-23 and LV-24 are transferred. When limit valve LV-23 is transferred, the stop members 136 of the first stop means 119 will not operate until the carton C under the second partition inserter has cleared the stop members 136' of the second stop means 120. When limit valve LV-24 is transferred, pilot PV-21B is activated as well as pilot PV-25A. This causes pilot valve PV-21 to supply air to the fluid cylinder 254' of the second partition inserter 241 to lower the stripper plate 251' thereof. Pilot valve PV-25 is effective in this position to supply air to fluid cylinder 261' of the second partition inserter 241 to pivot the guide members 258' down and open the same. This is effective to force the second partition E into the carton C between the containers A transversely of the first partition D inserted therein. The slots D' and E' intermesh in such a way that the partitions D and E are now in an interlocking position.

When the second partition inserter 241 completes its down stroke, limit valve LV-26 is transferred to activate air solenoid RV-21A and pilot PV-21A. This is effective to reset relay valve RV-21 and cause pilot valve PV-21 to supply air to the fluid cylinder 254' of the second partition inserter 241 and raise the stripper plate 251'.

As the stripping plate 251' is moving upwardly, limit valve LV-25 is transferred to supply air to pilot PV-22B and pilot PV-25B. This is effective to cause pilot valve PV-25 to supply air to solenoid 261' and raise the guide members 258' to a closed position. At the same time, pilot valve PV-22 supplies air to fluid cylinder 141' to lower the stop members 136' of the second stop means 120 and allow the belt 121 to transfer the carton C with the containers A and partitions D and E therein along the path X and out of the partition inserter section.

The carton C is then deposited onto the secondary belt conveyor 102 and the cross-bars 150 of the bar conveyor 104 move up between the belts 142 and 121 behind the container C and move the container C through the flap folding section. As the container C is moved through the flap folding section, it is displaced from the belt 142 of the secondary belt conveyor 102 onto the slide plate 270 with the side flaps F thereof depending downwardly past the slide plate 270. As the bar conveyor 104 moves the carton C across the slide plate 270, the deflection members 271 engage the depending side flaps F of the carton C and fold them inwardly under the slide plate 270. The bar conveyor 104 continues to move the carton C across the slide plate 270 and as it discharges the carton from the slide plate 270, the deflection members 271 finish folding the side flaps F up into a horizontal position and the bar conveyor 104 discharges the carton C with the bottom flaps thereof folded for sealing.

It will be seen that all of the motors of the machine operate continuously so that the carton and container conveyors driven thereby are continuously operated.

What is claimed as invention is:

1. Apparatus for packaging containers in collapsible cartons with partitions therebetween comprising:
conveying means for moving the cartons along a prescribed path and

inserting means for placing partitions between the containers in the carton carried by said conveying means, said inserting means comprising a magazine for storing the partitions in an ordered arrangement and for successively presenting the partitions above said conveying means for movement into the cartons carried on said conveying means, stripping means for successively displacing the partitions from said magazine one at a time into the carton between the containers, and guide means for guiding the partitions from said magazine into the carton between the containers; said guide means including guide members pivotally mounted adjacent said stripping means, and means for selectively pivoting said guide members down into the carton under said inserting means to guide the partitions into the carton and up out of the cartons for the cartons to pass thereby.

2. Apparatus for packaging containers in collapsible cartons with partitions therebetween comprising:

conveying means for moving the cartons along a prescribed path,
inserting means for placing partitions between the containers in the carton carried by said conveying means, and
loading means for placing the containers in said cartons carried by said conveying means prior to the placing of said partitions between said containers,
said loading means including container conveying means for moving the containers along a second path displaced from said path along which the cartons are moved, and means for selectively displacing the containers from said second path toward the path of the cartons and into each carton passing under said loading means,
said loading means further including drop table means for selectively supporting the containers in said second path said drop table means being selectively collapsible for the movement of the containers therethrough into the carton thereunder, and suction means for supporting the containers upon collapse of said drop table means and for moving the containers from said second path through said drop table means into the carton.

3. Apparatus for packaging containers in collapsible cartons with partitions therebetween comprising:

conveying means for moving the cartons along a prescribed path;
inserting means for placing partitions between the containers in the carton carried by said conveying means; and,
loading means for placing the containers in said cartons carried by said conveying means prior to placing said partitions between said containers, said apparatus further including:
carton opening means for opening the cartons from a flat, collapsed condition to an open position and positioning the opened carton on said conveying means prior to the placing of the containers in the cartons;
said carton loading means including carton magazine means for supporting the cartons in an ordered arrangement when the cartons are in a flat, collapsed condition and for successively presenting the cartons adjacent said path along which the cartons are moved, carton stripping means for successively displacing collapsed cartons from said magazine into carton opening position, and suction means for engaging the opposite sides of the carton in carton opening position to set up the carton into open condition.

4. Apparatus for packaging containers in collapsible cartons with partitions therethrough comprising:

conveying means for moving the cartons along a prescribed path;
inserting means for placing partitions between the con-

tainers in the cartons carried by said conveying means; loading means for placing the containers in said cartons carried by the conveying means prior to the placing of said partitions between said containers; and carton opening means including a magazine for storing collapsed cartons, means for stripping a carton from the magazine and feeding it to a carton opening device, said device including two sets of suction cups, means for engaging one set of cups with the rear face of a carton, means for engaging the other set of cups with the front face of said carton, means to create a vacuum in the cups of each of said sets, and means for moving said sets of cups away from each other, to draw the front and rear walls of the carton apart and thus open the carton.

5. Apparatus as in claim 4 wherein the said magazine is inclined at an angle of approximately fifteen degrees to the horizontal and said cartons are stacked on edge in said magazine and move down the incline to the stripping means.

6. Apparatus as in claim 5 further including a movable weight resting on the incline at the upper end of the stack of cartons and urging the cartons toward the stripping means.

7. Apparatus as in claim 6 including means for urging the lower edge of a stacked carton forward to counteract the tendency of the cartons to tilt, said means including a block engageable with the said carton edge and means for causing the block to engage the said carton edge and press it forwardly.

8. Apparatus as in claim 4 including means for folding up the bottom flaps of the cartons as the cartons move along the prescribed path.
